CURTAIN DISPLAY FRAME

Howard W. Nester, Worcester, Mass., assignor to
 Parker Wire Goods Company, Worcester, Mass.,
 a corporation of Massachusetts

Application February 11, 1932, Serial No. 592,376

7 Claims. (Cl. 211—45)

This invention relates to means for displaying drapery curtains and for supporting such curtains while in storage.

It is the present practice in the drapery trade 5 to stock certain patterns of draperies fully made up and ready for immediate use.

It is the general object of my invention to provide supporting frames on which such made-up or finished draperies may be assembled and arranged 10 for prompt display to a customer in a convenient and effective manner, as by placing selected frames successively in front of a conventional window opening. I also provide means on said frames for assembling draw-curtains or 15 valances in any desired combinations.

My invention further relates to arrangements and combinations of parts which will be herein-after described and more particularly pointed out in the appended claims.

Preferred forms of my invention are shown in 20 the drawings, in which

Fig. 1 is a plan view of my improved display frame;

Fig. 2 is a partial front elevation, looking in 25 the direction of the arrow 2 in Fig. 1;

Fig. 3 is a detail sectional end elevation taken along the line 3—3 in Fig. 1;

Fig. 4 is a front view showing the display frame in use;

Fig. 5 is a detail perspective view showing the 30 means for supporting and operating a draw-curtain;

Fig. 6 is a detail front elevation of a handle portion of the frame;

Fig. 7 is a detail side elevation, looking in the 35 direction of the arrow 7 in Fig. 6;

Fig. 8 is a detail sectional view, taken along the line 8—8 of Fig. 6;

Fig. 9 is a detail front elevation showing a modified 40 construction;

Fig. 10 is a plan view, looking in the direction of the arrow 10 in Fig. 9, and

Fig. 11 is a detail sectional elevation, taken along the line 11—11 in Fig. 10.

Referring to Figs. 1 and 2, my improved display frame comprises a top or cross bar 10 having side members 11 and braces 12 extending downward therefrom. The side members 11 are preferably bent outwardly and upwardly at their lower ends as shown in Figs. 4 and 6 to provide handle portions 14 by which the frame may be conveniently moved from place to place. The lower end of each brace 12 is secured to its associated side member 11. A supplemental horizontal brace 16 (Fig. 2) extends across the mem-

bers 11 and braces 12 and is secured to each of said parts at the points of crossing. The parts may be secured together in any convenient manner but preferably by welding the bars together.

End brackets 20 are secured to the cross bar 10 and side members 11 and project forwardly therefrom as shown in Fig. 1. These brackets 20 are notched, as indicated at 22 in Fig. 3, to receive supporting rods 24 and 25 for purposes to be described.

A hook 27 is secured to the center of the cross bar 10 and constitutes means by which the frame may be conveniently supported. The hook 27 is preferably extended downward and bent to form a ring 28 to which the inner edges of the draperies D may be hooked.

Holes 30 are provided in the brackets 20 to receive the outer hooks on the draperies, and a plurality of rings 32 are slidably mounted on the cross bar 10 to receive the intermediate hooks on the draperies. Rearwardly extending hooks 34 (Figs. 7 and 8) are provided on the handle portions 14, by which the tie-backs T for the draperies D may be secured.

For display purposes, samples of different patterns are mounted on different display frames and are hung in storage, from which they may be readily removed, to be hooked over a knob or projection 40 (Fig. 4) at the top of a conventional or dummy window frame W. The customer is thus enabled to see the draperies exactly as they will appear when in use, and the choice of a satisfactory pattern is made easy.

When drapery curtains only are shown, the additional rods 24 and 25 may be removed. If, however, it is desired to show the effect of a valance V with draperies D, the valance may be placed on the rod 25 and will thus appear in front of the draperies.

The same supporting frame may be used for displaying draw-curtains C (Fig. 5) by mounting the draw-curtains upon rings 44 slidable on the rod 24, while a valance V if desired may be placed on the rod 25. Openings 50 (Figs. 3 and 5) are provided in the end brackets 20 to receive a cord 52 which extends through the openings 50 and also through the ring 28 and which has its ends secured to the innermost ring 44a on the curtain C. By pulling the cord 52, the curtain may be moved toward or away from the center of the window as desired. It will be understood that the arrangement shown in Fig. 5 is duplicated for the other half of the window.

I may also provide plates 60 (Figs. 1 and 3) extending rearward from the brackets 20 and pro-

vided with additional notches 61 to receive one of the rods 24 or 25 if it is desired to display a glass curtain between the window and the draperies.

5 In Figs. 9, 10 and 11, I have shown a modified construction by which curtain bars 70 and 71 having curved ends may be used in my display frame. In this construction, the end brackets are omitted but U-shaped wire supports 72 and 10 73 are secured to the cross bar 10 at either side of each side member 11.

The U-shaped member 72 is provided with an upturned projection or stud 75 at the front side of the frame and with a similar projection or stud 15 76 at the rear side. The U-shaped member 73 has a stud or projection 77 at the front side of the frame. The curtain bars 70 and 71 are provided with transverse vertical openings 80 in their inner end portions, adapted to slip over the studs 20 or projections 75, 76 or 77.

An eyelet 82 is secured to each end of the cross bar 10, outside of the member 72. These eyelets 82 take the places of the openings 50 in the brackets 20 for guiding the draw-curtain cords 52, and 25 they may also be used for attaching the end hooks of drapery curtains, in place of the openings 30 previously described.

With this construction, the outer curtain rods 70 and the inner curtain rods 71 may be attached 30 to the upright projections or studs 75 and 77, or the outer curved curtain rod 70 may be attached to the rear projections or studs 76. If desired, however, a straight rod 84 may simply rest on the rearward projections 76.

35 I am thus able to display curtains or valances on the curved rods 71 and 72, or to display a draw-curtain on a rod 84 between the drapery and the glass.

This construction thus presents all of the 40 advantages of the construction previously described and is available where curved instead of straight curtain-rods are preferred.

It is thus evident that with my improved display frame, curtains and draperies of wide variety 45 may be assembled in any desired combinations and may be conveniently arranged for inspection by a customer, to whom the various fabrics will be presented exactly as they will appear when in use.

50 Furthermore, my improved display frames serve a very useful purpose as supports for draperies when in storage. It is found that by placing draperies upon display frames immediately upon receipt from the manufacturer and then hanging them in storage at full length, the curtains do not become creased and the substantial expense of re-pressing before delivery is avoided.

Having thus described my invention and the 55 advantages thereof, I do not wish to be limited to the details herein disclosed, otherwise than as set forth in the claims, but what I claim is:—

1. A curtain display frame comprising a readily portable structure on which a curtain may be suspended, means to attach curtains thereto, 60 means by which said structure is suspended, said portable structure comprising a top cross bar, side members and brace rods all rigidly secured together, and means on said frame to detachably

support two additional curtain rods in front of said frame and one additional curtain rod behind said frame.

2. A curtain display frame comprising a readily portable structure on which a curtain may be suspended, means to attach curtains thereto, 80 means by which said structure is suspended, said portable structure comprising a top cross bar, side members and brace rods all rigidly secured together, means to support an additional rod on said frame for a draw-curtain, and means on said frame to guide a draw-cord for said curtain. 85

3. A curtain display frame comprising a readily portable skeleton metal framework on which a curtain may be suspended, means to attach curtains thereto, means by which said framework is suspended from an overhead support, said skeleton framework comprising a top cross bar, side members and brace rods all rigidly secured together, said framework having transversely extending members effective to detachably support 90 a removable curtain rod selectively in front or behind said frame.

4. A curtain display frame comprising a readily portable skeleton metal framework on which a 100 curtain may be suspended, means to attach curtains thereto, means by which said framework is suspended from an overhead support, said skeleton framework comprising a top cross bar, side members and brace rods all rigidly secured together, 105 and means to detachably support thereon a plurality of curtain rods of different effective lengths and having curved end portions substantially abutting the end portions of said frame.

5. A curtain display frame comprising a readily 110 portable skeleton metal framework on which a curtain may be suspended, means to attach curtains thereto, means by which said framework is suspended from an overhead support, said skeleton framework comprising a top bar, side members and brace rods all rigidly secured together 115 and an additional horizontal stiffening rod positioned in the top portion of said frame but below said top cross rod and extending across said side members and brace rods and firmly secured 120 thereto.

6. A curtain display frame comprising a readily portable skeleton metal framework entirely open in its lower portion and on which a curtain may be suspended, means to attach curtains thereto, 125 and means by which said framework is suspended from an overhead support, said skeleton framework comprising a top bar, side bars and brace rods all rigidly secured together and said side members being downwardly extended and provided with handle portions. 130

7. A curtain display frame comprising a readily portable skeleton metal framework entirely open in its lower portion and on which a curtain may be suspended, means to attach curtains thereto, 135 and means by which said framework is suspended from an overhead support, said skeleton framework comprising a top bar, side bars and brace rods all rigidly secured together and said side members being downwardly extended and provided with means for attaching tie-backs thereto. 140

HOWARD W. NESTER.
